BY *Fatherstonhaugh Esq.*

ATTORNEYS.

UNITED STATES PATENT OFFICE.

DONALD EVANS PARRISH, OF BUFFALO, NEW YORK, ASSIGNOR TO HERBERT MORRIS INCORPORATED, OF BUFFALO, NEW YORK, A CORPORATION OF NEW YORK.

ASH-CAN HOIST.

Application filed October 30, 1924. Serial No. 746,807.

To all whom it may concern:

Be it known that I, DONALD EVANS PARRISH, a citizen of the United States of America, and a resident of the city of Buffalo, in the county of Erie, in the State of New York, United States of America, have invented certain new and useful Improvements in Ash-Can Hoists, of which the following is the specification.

- 10 My invention relates to improvements in ash can hoists and the object of the invention is to provide an improved construction of door operating mechanism as well as a counterweight mechanism.
- 15 A further object is to devise means for supporting the warning gong in the counterweight, said gong being adapted to ring upon the sidewalk doors being opened or shut with the consequent movement of the

20 counterweight.

My invention consists of an ash can hoist constructed and arranged all as hereinafter more particularly described and illustrated in the accompanying drawing in which:

25 Fig. 1 represents a vertical section through the pit containing the hoisting gear.

Fig. 2 is a vertical section through the line 2—2 Figure 1.

30 Fig. 3 is a plan view showing the sidewalk doors open.

Fig. 4 is an enlarged vertical section through the counterweight showing the gong in position therein, and

35 Fig. 5 is a perspective detail of an end of the transverse channel which supports the hoist assembly, showing the same secured to gutter channels extending around the top of the pit.

40 Like characters of reference indicate corresponding parts in the different views.

1 is the pit in which the hoist assembly is mounted. 2 are angle members extending around the open top of the pit 1, said members being imbedded in the concrete or other material of which the pit 1 is made.

45 3 are gutter channels surrounding the top of the pit 1, said channels 3 positioned inside of the angle members 2. 4 is a channel member extending between the opposed gutter channels 3 and having its ends resting on the toe-pieces 5 which are secured to such gutter channels.

50 6 is the vertical stationary mast for the hoisting gear, said mast secured at its bottom to the bracket 7 which is in turn se-

cured to the interior face of one wall of the pit 1. 8 is the movable mast secured at its lower end to the sleeve member 9 which is adapted to slide on the stationary mast 6.

60 10 is an inwardly extending bracket secured to the inner face of the channel 4 and provided with a socket 11 adapted to secure the upper end of the stationary mast 6 in place, said bracket 10 carrying the upper blocks 12 of the mast hoisting gear, the lower block 13 being journaled on the sleeve member 9 and the usual chain 14 extending between the blocks 12 and 13.

65 15 is a depending bracket secured to the channel 4 upon which is journaled the pulley 16 over which extends the chain 17 which is connected at one end to the counterpoise 18 and at the other end to the sleeve 19 which extends freely around the 70 stationary mast 6.

75 The counterpoise 18 is hollow and the vertical slide 20 secured at its upper end to the channel 4 and at its lower end to the bracket 7 extends freely therethrough. The 80 counterpoise being adapted to slide on such slide member. 21 is a suitably positioned upper stop on the slide 20 and 22 is a lower stop. 23 is an upper spring switch normally in engagement with the contact plate 24 which is suitably insulated from the counterpoise casing 18. A vertical pin 25 extends freely through the casing 18, being secured to an insulated portion of the spring switch 23.

85 26 is a lower spring switch insulated from the counterpoise casing 18 and normally contacting with the contact plate 27 also insulated from such casing.

90 28 is a vertical pin adapted to extend 95 freely through the casing 18 and secured to an insulated portion of the spring switch 26. 29 is a wire extending between the two contact plates 24 and 26. 30 is a lead from the lower switch 26 to the vibrator coil 31 of 100 the gong 32. 33 is a lead from the other terminal of the vibrator 31 to the batteries 34, and 35 is a wire connecting the other terminal of the battery with the switch 23.

105 36 are the sidewalk doors hinged to the angle members 2 and provided respectively at their outer ends with the guard gates 37 and 38, the guard gate 37 being rigidly secured to its door 36 whereas the guard gate 38 is hinged to its door 36, the coacting 110

edges of the gates 37 and 38 preferably overlapping each other. 39 are opposed rods pivotally secured together at their lower ends on the sleeve 19, their upper ends 40 being disposed at an angle to their main portions and the extremities of such ends 40 being pivotally secured to the underneath sides of the doors 36.

41 are short chains secured together at 10 their upper ends in one of the links of the counterpoise chain 17 and their free ends being secured to the opposed rods 39 in the vicinity of their lower ends. 42 is a swingable jointed arm pivotally secured to the 15 movable mast 8 and its free end carrying the ash can hoisting gear 43.

The operation of my device is as follows:

Assuming that the hoisting mechanism 20 is in the inoperative or lowermost position with the sidewalk doors 37 and 38 closed, to raise the mechanism into the operative position the block chain 14 is pulled in the desired direction with the result that 25 the sleeve 9 is raised and the movable mast 8 accordingly elevated. In the lowermost position the bottom of the sleeve member 9 engages the sleeve 19 and as the sleeve member 9 is raised the sleeve 19 is accordingly raised under the influence of the counterpoise 18 with the result that such sleeve moves from the dotted position illustrated 30 in Figure 1 into the position shown in full lines in the same figure. When this occurs the rods 39 are pushed upwardly, consequently opening the doors 36 the full extent until the portions 40 of the rods are in the position shown in full lines in Figure 1, the guard gates assuming the position illustrated in that figure, the hinge on the gate 38 being preferably a spring hinge to keep the gate in its normal closed position.

As the sleeve 19 is moved up the mast 45 the counterpoise slides down the slide member 20 and when the sleeve is raised the full extent the pin 28 of the switch 26 engages the lower stop 22 on the slide member 20 and thus throws the lower spring 50 switch out of contact with the plate 27, thus breaking the gong circuit, it being understood that the warning gong rings continually during the process of moving the hoisting gear and doors into their operative position.

On pulling down the movable mast 8 by the mast hoisting gear the lower end of the sleeve member 9 will engage the sleeve 19, sliding it down on the stationary mast 6 and thus closing the doors 36 over the top of the descending movable mast and ash can hoisting gear. Immediately the sleeve 19 is forced downwardly on the mast 6 the counterpoise 18 will be correspondingly raised and thus the pin 28 will be

thrown out of engagement with the stop 22, the switch 26 being consequently restored into contact with the contact plate 27, closing the gong circuit and causing the gong to ring during the above operation. 70

When the sleeve 19 reaches its lower limit as illustrated in dotted lines in Figure 1, the counterpoise 18 will be raised to its full extent with the result that the pin 25 will engage the stop 21 and force the spring switch 23 out of contact with the contact plate 24, thus breaking the gong circuit when the gong will cease ringing. 75

For positively insuring that the doors 80 36 open when the hoist is raised, I provide a pin 44 on the sleeve 9 which is adapted to come in contact with a lug 45 on one of the rods 39 when such sleeve 9 travels upwardly on mast 6; thus pushing the rods 85 upwardly and opening the door. This particular feature is specially provided for the winter time, when ice or snow would tend to prevent the opening of the gates under the influence of the counterweight. 90

From the above description it will be apparent that I have devised a simple and effective means for mounting the warning gong complete in the counterpoise and causing such gong to ring on the movement of the counterpoise either in an upward or downward direction. 95

I have also devised an improved door operating mechanism actuated by such counterpoise.

What I claim as my invention is:

1. In a hoistway closure for ash can hoists, sidewalk doors hinged above the cavity containing the ash can hoist, a stationary mast upon which the hoisting gear is mounted, a sleeve slidable on the mast, opposed rods pivoted at their upper ends to the doors, and at their lower ends to the sleeve, a counterpoise slidable in the hoistway, and means connecting the counterpoise with each of the opposed rods. 110

2. In a hoistway closure for ash can hoists, sidewalk doors hinged above the cavity containing the ash can hoist, a stationary mast upon which the hoisting gear is slidably mounted, a sleeve slidable on the mast, door actuating rods depending from the sidewalk doors into the hoistway and having their lower ends pivotally connected to the sleeve, the hoisting gear being adapted to rest upon the sleeve when the doors are closed, and a counterpoise slidable in the hoistway and connected to the door actuating rods, being adapted to open the doors when the hoisting gear is moved upwardly on the mast away from the sleeve. 115

3. In a hoistway closure for ash can hoists, sidewalk doors hinged above the cavity containing the ash can hoist, a stationary mast upon which the hoisting gear is slidably mounted, a sleeve slidable on the

mast, door actuating rods depending from the sidewalk doors into the hoistway and having their lower ends pivotally connected to the sleeve, and means on the hoisting gear coming in contact with means on one of the rods for moving the rods upwardly to open the doors when the hoisting gear is moved upwardly on the mast.

4. In a hoistway closure for ash can hoists, sidewalk doors hinged above the cavity containing the ash can hoist, a stationary mast upon which the hoisting gear is slidably mounted, a sleeve slidable on the mast, door actuating rods depending from the sidewalk doors into the hoistway and having their lower ends pivotally connected to the sleeve, and a pin on the hoisting gear coming in contact with a lug on one of the rods for moving the rods up-

wardly to open the doors when the hoisting gear is moved upwardly on the mast. 20

5. In a hoistway closure for ash can hoists, sidewalk doors hinged above the cavity containing the ash can hoist, a stationary mast upon which the hoisting gear is slidably mounted, a sleeve slidable on the mast, door actuating rods depending from the sidewalk doors into the hoistway and having their lower ends pivotally connected to the sleeve, a counterpoise slide, a counterpoise slidable thereon, a pulley, a chain secured at one end to the counterpoise and passing over the pulley, and a pair of short chains, each secured at one end to the end of the counterpoise chain, and its other 30 end secured to a rod intermediately of its length. 35

DONALD EVANS PARRISH.
